United States Patent Office

Des. 173,788
Patented Jan. 4, 1955

173,788

ACCOUNTING MACHINE

Robert D. Budlong, Skokie, Ill., assignor to Victor Adding
Machine Co., Chicago, Ill., a corporation of Illinois

Application October 29, 1953, Serial No. 27,380

Term of patent 3½ years

(Cl. D64—11)

Fig. 1.

Fig. 2.

Fig. 3.

To all whom it may concern:

Be it known that I, Robert D. Budlong, a citizen of the United States, residing at Skokie, in the county of Cook and State of Illinois, have invented a new, original, and ornamental Design for an Accounting Machine, of which the following is a specification, reference being had to the accompanying drawings, forming part thereof.

Fig. 1 is a perspective view of an accounting machine, showing my new design;

Fig. 2 is a side elevational view thereof; and

Fig. 3 is a rear elevational view.

I claim:

The ornamental design for an accounting machine, substantially as shown.
